UNITED STATES PATENT OFFICE.

JAMES MILAM, OF KANSAS CITY, KANSAS.

CONCRETE-WALL-BUILDING DEVICE.

No. 839,496.

Specification of Letters Patent.

Patented Dec. 25, 1906.

Application filed March 12, 1906. Serial No. 305,518.

To all whom it may concern:

Be it known that I, JAMES MILAM, a citizen of the United States, residing at Kansas City, in the county of Wyandotte and State 5 of Kansas, have invented certain new and useful Improvements in Concrete-Wall-Building Devices, of which the following is a specification.

My invention relates to apparatus for use 10 in building integral concrete walls as distinguished from those composed of separate blocks laid in cement or mortar, and more particularly to molds of that class which can be withdrawn after the concrete therein has 15 become sufficiently hardened to support the molds for and the succeeding "course" of concrete.

One object of my invention is to provide 20 improved means for adjusting the walls of the mold accurately to vertical position when necessary, so that the wall is kept plumb during construction.

A further object is to produce a mold having 25 a seat-bar which may be withdrawn from either side of the wall to facilitate construction and reduce the cost of erection.

A still further object is to provide mold- 30 plates which are interchangeable from the inner to the outer side of the wall, or vice versa, and thus avoid the cost of a duplicate set of plates.

With these and other objects in view the invention consists in certain novel and peculiar features of construction and organization, 35 as hereinafter described and claimed, and in order that it may be fully understood reference is to be had to the accompanying drawings, in which—

Figure 1 is a side elevation of an apparatus 40 embodying my invention. Fig. 2 is a vertical section thereof, taken on line II II of Fig. 1. Figs. 3 and 4 are detail sectional views of the connections between one of the over- 45 arches and a seat-bar, the forms being indicated by dotted lines. Fig. 5 is a detail sec- tional view of a portion of Fig. 2. Fig. 6 is an inside elevation of one of the stone-pitch forms. Fig. 7 is a view similar to Fig. 2, illustrating the plumbing of the forms upon 50 an uneven wall-surface. Fig. 8 is an enlarged horizontal section taken on line VIII VIII of Fig. 2. Fig. 9 is a perspective view of the seat-bar. Fig. 10 is an edge view of one of the plain forms. Fig. 11 is a detail sectional 55 view of a portion of Fig. 2. Fig. 12 is a view

of one of the parts detached. Fig. 13 is a plan view of one of the arch-bars.

In the said drawings, 1 and 2 indicate iron plates or forms adapted to be assembled to form the inner and outer walls of a mold, the bottom of which is formed by the upper surface of that portion of the wall previously formed, excepting that the first course of the wall is constructed as hereinafter described.

3 indicates a portion of a concrete wall 65 shown as constructed with this apparatus, the inner side of the wall appearing in Fig. 1.

The series of forms which are in use at any time are partially supported by a lower series of forms which are left upon the wall until 70 the upper series have been filled with material. Thus in Fig. 2 the lower forms 1 and 2 have been filled and remain upon the wall, while the upper forms 1 and 2 stand ready to receive the material to form the next course. 75

The forms are held in position by means of overarches, which are supported by trans- 80 verse bars laid upon the finished portion of the wall, as shown in Fig. 8. These bars are tapered in breadth and thickness, (see Figs. 8 and 9,) so that after they are embedded in the wall they may be easily withdrawn.

Each bar or seat-bar 4 is provided near its ends with openings 5, adapted to receive, respectively, a pair of blocks 6, to which the 85 upright members of the overarch are connected, as shown in Figs. 3 and 4. From openings 5 recesses 7 are cut inwardly in the seat-bar to receive the lugs 8, formed on the lower corners of each form 1 and 2. The 90 recess 7 at the smaller end of the bar is preferably extended inwardly a short distance, as shown, thus forming a small cavity which is to be filled with concrete *a*. In order to permit of the extraction of the seat- 95 bar, its smaller end is formed with an opening 9 of sufficient width to clear the pillar of concrete *a* when the bar is extracted. A small pillar *b* may also be formed through the inner end of the other recess 7, but is 100 unobjectionable, because it will readily break under the pressure applied by the seat-bar when the latter is extracted.

In order to permit of the use of inter- 105 changeable forms, the larger end of the seat- bar is reduced, so that parts 10 thereof are of the same thickness and breadth as parts 11 at the opposite end of the bar. The recesses 12 in the lower edges of the forms which fit over said parts 10 and 11 may thus 110

be uniform in size, as is necessary in interchangeable forms. By the reduction in depth of the seat-bar a shoulder 13 is formed, the reduction in width producing 5 shoulders 14. In this connection it will be noticed that a narrow space is left between shoulders 13 and 14 and the adjacent form-plates, this spacing being desirable to facilitate the assembling of the parts and their 10 separation, it being also noted that the thin flange or bead of concrete which will enter said spaces will readily break as the seat-bar is extracted.

For every two pairs of forms an overarch 15 is provided, said overarch comprising a pair of standards 15 and 16 of unequal length, an extensible connecting member 17 18, and a device for adjusting the inclination of the standards, as hereinafter described. The 20 extensible connecting or arch member 17 18 is pivotally connected to the standards 15 and 16 at 19 and 20, respectively, and the lower end of each standard is provided with hinge-lugs 21. The blocks 6, hereinbefore 25 mentioned, each comprise a body portion, a pair of laterally-projecting lugs 22, and an upwardly-projecting hinge-lug 23, said lugs 23 being connected by pins 24 to the hinge-lugs 21 of the standards 15 and 16.

30 The standard 15 above the connection 19 is provided with hinge-lugs 25, to which is pivoted the squared head 26 of a screw 27. The arch-bar 17 18 is also provided near standard 16 with hinge-lugs 28, between 35 which is pivoted a block 29, provided with a cylindrical stem 30, on which a collar 31 is retained by a cotter 32. Swiveled on the stem between block 29 and collar 31 is one 40 end of a turnbuckle 33, the opposite end engaging the screw 27. The turnbuckle and screw 27 form the hypotenuse of a right-angle triangle, as shown in Fig. 2, and it is clear that when the buckle 33 is turned it will either increase or decrease the distance 45 between pivots 28 and 25. The effect of such adjustment is hereinafter described.

An overarch is set up by inserting the pivotally-attached blocks 6 in the openings 5 of a seat-bar 4 in contact with the forms 50 or in position to receive the forms, as the case may be, and the lugs 22 will rest upon the seat-bar at 34, Figs. 1 and 11. The blocks 6 being the full width of the openings 5 are prevented by shoulders 35 from slipping inwardly and are rigidly secured in place by 55 wedges 36, driven against their outer faces through openings 5.

Each form-plate 1 and 2 is provided near its ends upon its outer face with two hook-lugs 37, which engage the edges of standards 15 and 16 to hold the plates upright, the hinge-lugs of the standards being made sufficiently narrow to slide between the ends of the hook-lugs 37, so that the standards may 65 be lifted without disturbing the tier of forms

which are left upon the wall to support the following tier.

Each of the blocks 6 is provided on its inner face with a recess or groove 38, as shown in Figs. 11 and 12, and each form 1 70 and 3 is provided on its outer face with a projection 39 to fit within the recess 38 of the juxtaposed block 6, clamped in place by a wedge 36. Thus when the wedges are in position it is obvious the standards are anchored to the lower tier of forms and cannot become accidentally raised while in use. 75

The arch member is located far enough above the forms to permit the workmen to 80 operate freely thereunder when leveling or smoothing the concrete and is varied in length by endwise adjustment of the bars 17 18, a bolt 40, carried by one of the bars, engaging one of a series of holes 41 in the other, as shown in Fig. 13. It is not necessary to 85 make the seat-bars 4 adjustable as to length to accommodate walls of different thickness, as they may be cast in different lengths and one of the proper size be selected to accommodate the length of the arch member. 90

If in the erection of a wall one of the seat-bars should occupy a lower plane than its neighbors at either side because of unevenness in the top wall, the superposed form-plates can be brought to the level of the contiguous plates on the higher portions of the wall, because each form-plate is provided with a pair of outwardly-projecting lugs 42 near its lower corners, which lugs overlie the ends of the seat-bar in order that wedges 100 42^a (shown in Fig. 1) may be driven between said bar and said lugs, these wedges elevating the adjacent ends of the form-plates until they occupy the same level as the contiguous form-plates. 105

Half of the number of forms employed may be provided on the inner side with marginal flanges 43 and 44, so as to groove the wall in imitation of the blocks of a stone wall.

Where the wall is to be imitation "stone-pitch" on both sides, the flanged forms 2 are 110 set up at both the inner and outer sides of the wall. If the wall is to be plain-faced on both sides, the plain forms only are used. The fact that all of the form-plates are identical 115 in construction at their lower corners and that the seat portions of the seat-bars are of equal size and form makes it possible to use any plate at either side of a wall.

It is obvious that the seat-bar can be arranged with its body portion tapering to the outer side of the wall or to the inner side, according as it is found most convenient to extract the bars from the inner or outer side of a wall. Ordinarily they are withdrawn at 125 the inner side; but in some cases where an external scaffolding is employed it will be more convenient to extract the seat-bars from the outer side.

Because of the peculiarity of the connec- 130

tion between the overarch, wall-plates, and seat-bar it will be apparent that the wall-plate can be lifted vertically the length of their lugs 8 and then drawn endwise from engagement with the overarch-standards and

5 that the reversal of this manipulation will restore them to their original positions. In other words, because of the peculiar construction and relation of the parts mentioned the wall-plates can be set up or removed without disturbing or affecting the position of the overarch.

It will be seen that by means of an apparatus of this character "battered" walls may be erected, as by reducing the length of the arch member the standards, and consequently the wall-plates, will be caused to converge upwardly, it being of course obvious as each tier or course is laid that the 20 arch-bar will have to be shortened in order to continue the upward taper of the wall.

In erecting a wall it is preferable to first provide a bed of cement or concrete upon the foundation and to level said bed. A seat-bar 25 is placed transversely upon this bed at a proper point, and an overarch is then placed with its blocks 6 fitting in the openings 5 in said bar and clamped therein by wedges 36, the turnbuckle being manipulated to cause the 30 standards of the overarch to assume a vertical position if one end of the seat-bar is slightly lower than the other. A pair of form-plates 1 and 2 are then caused to engage the seat-bar and standards of the overarch. Similar molds are then set upon the 35 bed until the circuit of the wall is made or as much thereof as is desired, and then said molds are filled with concrete and the upper surface of the latter is leveled flush with the 40 upper edges of the forms. The overarches are removed after first extracting the wedges 36 by being slid vertically up through and between the hook-lugs 37 of the juxtaposed form-plates.

45 For the next course a second series of seat-bars are laid upon the wall and upon the upper edges of the form-plates embracing the same, the second series of seat-bars being preferably arranged staggered with relation 50 to those immediately below. The overarches are then placed upon this second series of seat-bars, and a second set of form-plates are secured to said seat-bars and overarches to provide the forms for a second course of concrete, which second course, it will be noticed, (by reason of the position of the adjacent tiers of seat-bars,) is produced with a break-joint effect, provided the form-plates are of the proper type to cause such effect. After 55 the second course of the wall is finished the seat-bars of the course beneath may be removed from the wall by simply pulling them endwise, and in this connection it will be noticed that the pillar *a* of concrete will not 60 prevent the extraction of the seat-bars, be-

cause the slots 9 are of such width that their opposite walls will pass the opposite sides of said pillars. The holes left in the wall by the removal of the seat-bars will be filled up in any suitable manner.

70 From the above description it will be apparent that I have produced a concrete-wall apparatus embodying the features of advantage enumerated as desirable, and I wish it to be understood that I do not desire to be limited to the exact details of construction shown and described, for obvious modifications may occur to a person skilled in the art.

Having thus described the invention, what I claim as new, and desire to secure by Letters Patent, is—

75 1. In concrete-wall apparatus, a seat-bar of tapering form and having seat portions at opposite ends of the tapered portion, said seat portions being of substantially the same cross-sectional area.

80 2. In concrete-wall apparatus, a seat-bar of tapering form and having seat portions at opposite ends of the tapered portion, said seat portions being of substantially the same cross-sectional area, and provided with openings.

85 3. In concrete-wall apparatus, a seat-bar of tapering form and having seat portions at opposite ends of the tapered portion, said seat portions being of substantially the same cross-sectional area and provided with openings; the seat portions at the smaller end of the tapered portion being slotted from the extremity of said seat portion to the opening 95 therein.

90 4. In concrete-wall apparatus, a seat-bar of tapered form and having seat portions at its opposite ends and provided with openings in said seat portions having extensions 105 through the contiguous ends of the tapered portion of the bar, the seat portion at the smaller end of the tapered portion having a slot extending from the extremity of said seat portion through the openings therein.

110 5. In concrete-wall apparatus; a bar comprising a tapered body portion terminating at its smaller end in a seat portion and provided at its larger end with a seat portion of substantially the same width as the first-named seat portion and narrower than the end of the body portion from which it projects, said seat portions being provided with openings.

115 6. In concrete-wall apparatus, a bar comprising a body portion which tapers in width 120 and in thickness from one end to the other and provided at its smaller end with a seat portion of substantially the same cross-sectional area as the smaller end of the body portion and provided at its opposite end with a 125 seat portion of less width and thickness than said end; said seat portions being provided with openings.

130 7. In concrete-wall apparatus, a bar comprising a body portion which tapers in width

and in thickness from one end to the other and is provided at its smaller end with a seat portion of substantially the same cross-sectional area as the smaller end of the body portion and provided at its opposite end with a seat portion of less width and thickness than said end; said seat portions being provided with openings which extend into the body portion, the seat portion at the smaller end of the bar having a slot extending from the extremity of said seat portion to the opening therein.

8. The combination of a seat-bar comprising a body portion which tapers from one end to the other, and a pair of seat portions forming extensions of said bar and of substantially the same cross-sectional area as the smaller end of said bar; said seat portions having openings, and a mold comprising two pairs of wall-plates, one pair resting on each seat portion and having their ends abutting, and provided with lugs depending into said openings.

9. The combination of a seat-bar comprising a body portion which tapers from one end to the other, and a pair of seat portions forming extensions of said bar and of substantially the same cross-sectional area as the smaller end of said bar, said seat portions having openings; a mold comprising two pairs of wall-plates, one pair resting on each seat portion and having their ends abutting, and provided with lugs depending into said openings, and means for clamping said wall-plates inwardly against the seat portions of the seat-bar.

10. In concrete-wall apparatus, a mold comprising a pair of abutting outside wall-plates, a pair of abutting inside wall-plates, a seat-bar for said wall-plates, blocks clamping said plates inwardly against portions of the seat-bar, a pair of standards pivoted to said blocks and overlapping the abutting ends and engaging the outer sides of said plates, an arch-bar pivotally connecting said standards, and means for varying the angle of the arch-bar with respect to the standards to cause the rear wall-plates to assume angular relations with respect to said bar.

11. In concrete-wall apparatus, a horizontal seat-bar having near its ends two openings, two blocks detachably fitting in said openings, two standards pivotally supported by said blocks, an arch-bar having its ends pivotally connected to the standards, and means for normally holding said parts in rigid relation and for varying the angle between the standards and the seat-bar at times.

12. In concrete-wall apparatus, a horizontal seat-bar having near its ends two openings, two blocks detachably fitted within said openings, two standards pivotally supported by said blocks, form-plates provided with hook-lugs which engage the standards, an arch-bar having its ends pivotally connected

to standards, and means for normally holding said parts in rigid relation and for varying the angle between the standards and the seat-bar at times.

13. In concrete-wall apparatus, a plurality of form-plates which are interchangeable for inside or outside use, in combination with a horizontal seat-bar provided near its ends with two equally-dimensioned seats adapted to take into equally-dimensioned recesses in the lower edges of the form-plates, said seat-bar being tapered from one of said seats to the other.

14. In concrete-wall apparatus, the combination of wall-plates adapted to engage opposite sides of a wall and provided with external lugs, a seat-bar adapted to bridge the space between said wall-plates provided with seat portions projecting beyond said plates and formed with openings, blocks resting upon said seat portions and depending through the said openings and provided with horizontal grooves to engage said lugs, and means to secure said blocks in the relation described.

15. In concrete-wall apparatus, the combination of wall-plates adapted to engage opposite sides of a wall and provided with external lugs, a seat-bar adapted to bridge the space between said wall-plates provided with seat portions projecting beyond said plates and formed with openings, blocks resting upon said seat portions and depending through the said openings and provided with horizontal grooves to engage said lugs, and wedges to be forced into said openings outward of the blocks to clamp the same against the outer side of the wall-plates.

16. In concrete-wall apparatus, the combination of wall-plates adapted to engage opposite sides of a wall and provided with external lugs, a seat-bar adapted to bridge the space between said wall-plates provided with seat portions projecting beyond said plates and formed with openings, blocks resting upon said seat portions and depending through said openings and provided with horizontal grooves to engage said lugs, a pair of end-abutting wall-plates upon each of the first-named wall-plates provided with hook-lugs opening toward each other, and an over-arch having upright standards engaging the outer sides of the abutting wall-plates and extending through the hook-lugs thereof and pivoted at their lower ends to said blocks, and means to clamp said blocks against the outer sides of the first-named and abutting wall-plates.

17. In concrete-wall apparatus, the combination of a seat-bar to rest upon a wall, provided with seat portions projecting beyond the sides thereof and provided with openings, abutting wall-plates above and provided with lugs depending through the openings of the seat portions, blocks secured

to the seat portions, an overarch overlapping the outer sides of the abutting ends of the wall-plates, hook-lugs upon said wall-plates engaging the overarch, lugs projecting from the lower corners of the wall-plates and disposed over said seat portions, and wedges to fit between the last-named lugs and the seat portions to vertically adjust the corresponding ends of the wall-plates.

18. The combination of a seat-bar having openings, blocks depending through said openings and provided with a horizontal

groove in its inner face, laterally-projecting lugs resting upon the seat-bar at opposite sides of said openings and upwardly-projecting lugs outward of the laterally-projecting lugs. 15

In testimony whereof I affix my signature in the presence of two witnesses.

JAMES MILAM.
